UNITED STATES PATENT OFFICE

1,935,839

PORTABLE LOCOMOTIVE DRAFTING
DEVICE

Arthur J. Filkins, Chicago, Ill.

Application June 9, 1932. Serial No. 616,252

5 Claims. (Cl. 104—52)

My invention relates to certain new and useful improvements in portable locomotive drafting devices as set forth in the following specification in conjunction with the showing of the preferred embodiment thereof in the drawing forming a part of the specification, the novel features being set forth in the appended claims.

In my prior patent of the United States 1,165,957, December 28th, 1915, I have shown and described a portable locomotive drafting device designed for attachment to the discharge end of the stack of a locomotive, and it is the primary object of the invention to improve upon the structure shown and described in my aforesaid patent in which the adjustable receiving pipe of the drafting apparatus was of an extended and expensive character and also quite heavy and inconvenient in manipulating in connection with a portable device for the reason that the usual acid character of the fumes of combustion forming in the locomotive stack in firing requires the pipe construction of cast iron for resisting such fumes and the modern tendency to increase the height and size of the locomotive stacks has made the use of a drafting suction pipe of a character shown in my aforesaid patent elongated, heavy and expensive and difficult of operation and adjustment particularly in view of the modern tendency to increase the diameter and height of the locomotive discharge stack.

A further object of my invention is to provide an improved portable locomotive drafting device of a character capable of ready attachment direct to the smoke box chamber at the end of the boiler flues and at the front end of the locomotive.

Other objects of the invention will appear from the following description of the preferred embodiment with reference to the accompanying drawing in which Fig. 1 is a fragmentary, diagrammatic view of the front end of a locomotive showing the usual smoke stack and the front end smoke box equipped with a peep hole provided with a removable cover designed to accommodate the use of my improved apparatus and also to provide an opening for inspection of the locomotive smoke box.

Fig. 2 is a front elevation of a locomotive with my improved portable drafting device attached thereto and illustrated alternative methods of discharging the products of combustion from the locomotive during the drafting operation.

Fig. 3 is a side elevation view of the portable drafting device of Fig. 2, a fragment of the locomotive smoke box being shown to which the

drafting device is attached with the discharge spout thereof leading toward an opening as a window in the wall of a building.

Fig. 4 is an enlarged, detailed sectional view being taken approximately on the line 4—4 of Fig. 5 looking in the direction indicated by the arrows and Fig. 5 is a detailed, sectional view on line 5—5 of Fig. 4 looking in the direction indicated by the arrows.

Referring to the drawing, 10 is a platform carried by a frame work 11 and it is adapted to be shifted from place to place for use in drafting various locomotives as in a round house when it is desired to fire any given locomotive. The frame is mounted upon wheels 12. An exhaust fan or blower is provided in a casing 13 mounted on the platform 10 and is driven by the motor 14 through the rotor shaft 15.

The intake or suction end of the fan is provided with an elbow 16 to which is connected for universal adjustment a pipe 17 terminating in an adjustable elbow 18 provided with a peripherally flanged portion 19 adapted to take a co-operating attaching pipe section 20 which has a peripherally enlarged under-cut flange 21 adapted to surround the flange on the portion 19 of the intake pipe leading to the exhaust fan or blower casing 13. The intake pipe section 20 will preferably be of a size adapted to enter a peep hole or other opening 22 in the smoke box casing 23 of a locomotive, such opening being surrounded by the usual peripheral flange 24 carrying one or more and preferably two spaced-apart inwardly projecting radial pins 25 designed to co-operate with bayonet joints 26 formed in the swivelled intake pipe section 20 whereby the intake pipe of the drafting device may be connected with the smoke box of the locomotive in the most simple and economical manner.

A vertical standard 45 is mounted on the platform 10 and supports a swivelly mounted sheave 26 adapted to receive a flexible cable 27 for supporting the discharge pipe of the drafting device which is shown in the drawing, Figs. 2 and 3, as consisting of the two telescoping sections 28, 29 respectively, the discharge pipe section 28 of the drafting device being swivelly connected at 30 to the exhaust fan casing 13, and the pipe section 29 telescopically mounted thereon being provided with the pivotally attached bail 31 by which the direction of the discharge pipe sections may be maintained and the longitudinal extensible section 29 supported in its adjusted position for discharging smoke, gases and the like as products of

- combustion from a locomotive being fired by means of the drafting device.
- When the device is brought up along side of a locomotive and attached in a manner illustrated in connection with Figs. 2, 3 and 4 with the intake pipe 17 adjusted to fit in the flanged peep hole opening 22 or other suitable opening in the smoke box and when the exhaust pipe sections 28 and 29 are adjusted as illustrated in Fig. 2 to extend upwardly into a smoke receiving device 32, the fan in the casing 13 may be started to operate, producing in the smoke box of the locomotive the desired vacuum or draft so that the firing takes place quickly and without inconvenience and all the products of combustion pass through the fan casing 13 and discharged into the smoke receiving hood or opening 32 which is capable of handling them and removing them from the building in the ordinary manner, being in the embodiment illustrated in Fig. 2 either the draft hood 32 attached to a suitable wall or post indicated diagrammatically at 33 and leading obviously to a pipe, not shown, carried by the wall or post and discharged on the outside of the building. Optionally the usual smoke jack, indicated at 34 for ordinarily taking the products of combustion direct from the stack of the locomotive and to be found in most round houses and running sheds, may be utilized, under which conditions the discharge pipe sections 28, 29 will be adjusted to substantially the position illustrated by dotted lines in Fig. 2. The discharge pipe sections 28, 29 may be further operated to discharge the smoke and other products of combustion from the device in drafting the locomotive as by passing the pipe section 29 through a window of the building as indicated at 35, Fig. 3 but in any event, regardless of the manner of disposal of the products of combustion taken from the locomotive by the drafting device, it is essential to secure the best results to close the stack 36 of the locomotive while the drafting device is being used as by means of the detachable cap 37 over the top thereof shown in Fig. 2. By connecting the smoke box of the locomotive on one side or to the front end thereof I am able to effect certain economies in construction, to produce a lighter device because less of the intake connection leading to the improved apparatus is necessary and I am enabled to secure improved results by reason of being able to procure in an economical and easily accessible manner a direct connection with a smoke box leading to the flues and fire box of the locomotive by which a suitable vacuum may be maintained when the top of the smoke stack is closed and the combustion in the fire box caused to accelerate in the most expeditious manner until sufficient pressure of steam in the locomotive boiler has been produced so that the forced draft can be used in the ordinary way when my improved device will be disconnected and moved to another locomotive which requires firing.

I claim:

1. A portable device for drafting locomotives when firing the same, comprising a platform movable from place to place, a power driven fan thereon, means to connect the intake of the fan to the smoke box of a locomotive on a part of the smoke box remote from the smoke stack, detachable means for closing the smoke stack when the intake of the fan is operatively connected with the smoke box and means to lead the exhaust from the fan casing.
2. A portable device for drafting locomotives when firing the same comprising a platform movable from place to place, a power driven fan thereon comprising a casing provided with intake and discharge openings, means for connecting the intake opening of the fan casing to the smoke box of a locomotive through one of the walls of the smoke box remote from the smoke stack comprising a pipe section provided with a plurality of spaced angular joints and a detachable connection for said pipe section with the wall of said smoke box comprising a plurality of spaced-apart slots, and co-operating interlocking projections arranged respectively on said pipe and adjacent an opening provided in the smoke box of the locomotive. 80
3. A portable device for drafting locomotives when firing the same comprising a platform movable from place to place, a power driven fan thereon, means for leading the exhaust from the fan comprising a plurality of telescoping pipe sections for longitudinal adjustment, one of the pipe sections being swivelly connected with the fan for varying the position of the discharge end thereof, and means for connecting the intake of the fan to one of the side walls of the smoke box of a locomotive on a portion of the smoke box wall remote from the smoke stack comprising a pipe provided with a plurality of spaced-apart elbow joints, and a locking terminal portion at the outer extremity of the said pipe adapted to co-operate with the smoke box wall of a locomotive to operably connect the fan with the interior of the smoke box. 95
4. A portable device for drafting locomotives when firing the same comprising a platform movable from place to place, a power driven fan thereon, means for leading the exhaust from the fan comprising a plurality of telescoping pipe sections for longitudinal adjustment, one of the pipe sections being swivelly connected with the fan for varying the position of the discharge end thereof, and means for connecting the intake of the fan to one of the side walls of the smoke box of a locomotive on a portion of the smoke box wall remote from the smoke stack comprising a pipe provided with a plurality of spaced-apart elbow joints, and a locking terminal portion at the outer extremity of the said pipe adapted to co-operate with the smoke box wall of a locomotive to operably connect the fan with the interior of the smoke box. 100
5. A portable device for drafting locomotives when firing the same comprising a platform movable from place to place, a power driven fan thereon, means for leading the exhaust from the fan comprising a plurality of telescoping pipe sections for longitudinal adjustment, one of the pipe sections being swivelly connected with the fan for varying the position of the discharge end thereof, and means for connecting the intake of the fan to one of the side walls of the smoke box of a locomotive on a portion of the smoke box wall remote from the smoke stack comprising a pipe provided with a plurality of spaced-apart elbow joints, and a locking terminal portion at the outer extremity of the said pipe, a co-operating locking portion adjacent and opening through the smoke box wall of a locomotive to operably connect the fan with the interior of the smoke box, and detachable means for closing the smoke stack when the said portable drafting device is operably connected with the interior of the smoke box. 115
6. A portable device for drafting locomotives when firing the same comprising a platform movable from place to place, a power driven fan thereon, the said platform being of a suitable height to position the power fan thereon adjacent one of the side wall portions of the smoke box of a locomotive at a point remote from the smoke stack, means to connect the intake of the fan to the smoke box of a locomotive on a portion thereof remote from the smoke stack, detachable means for closing the smoke stack when the portable drafting device is attached to the smoke box of the locomotive for drafting operation, and means to lead the exhaust from said power driven fan. 130
7. A portable device for drafting locomotives when firing the same comprising a platform movable from place to place, a power driven fan thereon, the said platform being of a suitable height to position the power fan thereon adjacent one of the side wall portions of the smoke box of a locomotive at a point remote from the smoke stack, means to connect the intake of the fan to the smoke box of a locomotive on a portion thereof remote from the smoke stack, detachable means for closing the smoke stack when the portable drafting device is attached to the smoke box of the locomotive for drafting operation, and means to lead the exhaust from said power driven fan. 145

ARTHUR J. FILKINS.
